EDWARD W. BALL AND LOUIS E. VACHERON, OF NEW YORK, N. Y., ASSIGNEES TO THE LALANCE & GROSJEAN MANUFACTURING COMPANY, OF SAME PLACE.

SINK.

SPECIFICATION forming part of Letters Patent No. 627,070, dated June 13, 1899.
Application filed March 8, 1898. Serial No. 673,073. (No model.)

To all whom it may concern:

Be it known that we, EDWARD W. BALL and LOUIS E. VACHERON, of Woodhaven, in the borough of Queens, city of New York, county 5 of Queens, and State of New York, have invented certain new and useful Improvements in Sinks, of which the following is a specification.

Our invention relates to sinks, and has for its object to produce a structure wherein, while refuse may have a free and unobstructed flow to the drain-pipe, the overflow is protected from being filled with refuse.

The invention will be explained with reference to the accompanying drawings, which show a sink embodying our invention.

In the drawings, Figure 1 is a sectional detail view of a form of sink which we have devised; and Fig. 2 is a broken-away sectional 20 plan view of the same, the section of Fig. 1 being taken on the line 1 1 of Fig. 2 and the section of Fig. 2 being taken on the line 2 2 of Fig. 1.

Heretofore sinks have been devised in which 25 the overflow pipe or passage discharges directly into the discharge-pipe of the sink below the strainer, the opening of the overflow leading to the discharge-pipe being located beneath the strainer and unprotected, in 30 many cases becoming choked up by the lodgment of refuse which passed through the strainer, and since the overflow operated only occasionally when the strainer became stopped up by refuse it was quite an easy 35 matter for the discharge-opening of the overflow to become entirely choked up, rendering the overflow useless, so that when the overflow was choked up as described and the strainer likewise became choked up the water 40 discharged by the water-pipes into the sink or basin would overflow the edges of the said sink or basin and damage would result. It is the object of our invention to overcome this difficulty by providing a free or unobstructed 45 drain-pipe and overflow, and means whereby the discharge-orifice of the overflow leading to the drain-pipe may be efficiently protected from the deposit therein of refuse. These ends are accomplished by covering the discharge-orifice of the overflow by an imperforate open unobstructed thimble contained within the discharge-pipe of the sink.

In the accompanying drawings, A is a sink

or basin provided with an unobstructed open discharge-pipe B, leading therefrom and covered by a loose removable strainer C.

D is the overflow, having its lower leg substantially horizontal and its discharge-orifice E leading to the discharge-pipe B and adapted to discharge liquid thereinto, which liquid enters the overflow at F—the inlet end thereof. The discharge-orifice E of the overflow is shown as protected or guarded by a thimble G, herein shown as an annular imperforate flared funnel, whose upper edge g rests loosely 65 and removably upon the upper edge b of the discharge-pipe B of the sink and whose lower end is free and open and extends into the discharge-pipe below the mouth E of the overflow.

It will be obvious now that in the structure shown all refuse which may pass through the apertures c of the strainer C will be freely conducted through the open unobstructed discharge-pipe B past the orifice E of the overflow D to the lower portion B' of the discharge-pipe, so that there will be no chance for the said refuse to lodge in the orifice E, and consequently the overflow will at all times be open and unrestricted. As a consequence if the strainer C becomes stopped up for any 70 cause the overflow will carry off the water when the water-level in the sink or basin A rises to a predetermined height, as will be readily understood. It will thus be obvious that we have provided a sink or basin wherein 75 the overflow will at all times be operative to carry off the excess of water.

Having described our invention, what we claim, and desire to secure by Letters Patent, is—

In combination a sink or basin having a discharge-pipe B, an overflow D having a substantially horizontal leg leading by an orifice E into the discharge-pipe B, a loose removable imperforate annular flared funnel G 95 constituting a free and unobstructed conduit and covering the entrance E of the overflow into the discharge-pipe and extending below the said orifice and the loose removable strainer C covering and bearing upon the 100 funnel G.

EDWARD W. BALL.
LOUIS E. VACHERON.
